United States Patent Office

Des. 213,855
Patented Apr. 15, 1969

213,855

PROMPTING MACHINE

Alvin Eisenberg, 6104 Little Neck Parkway,
Little Neck, N.Y.

Filed Jan. 4, 1968, Ser. No. 10,053

Term of patent 14 years

Int. Cl. D19—08

U.S. Cl. D96—9

FIG. 1

FIG. 2

FIG. 3

FIG. 4

FIG. 5

FIGURE 1 is a perspective view of a prompting machine showing my new design;

FIGURE 2 is a rear elevational view thereof;

FIGURE 3 is a front elevational view thereof;

FIGURE 4 is a bottom plan view thereof; and

FIGURE 5 is a side elevational view thereof.

I claim:

The ornamental design for a prompting machine, substantially as shown.
